SWITCH-HANDLE LOCK

Egmont Arens, New York, N. Y., assignors to Federal Electric Products Company, Newark, N. J., a corporation

Application February 10, 1949, Serial No. 75,652

17 Claims. (Cl. 70—210)

1 The present invention relates to enclosed electric switches and more particularly to such switches which are provided with switch-operating handles disposed externally of the switch enclosure or casing.

One object of the present invention is the provision of improved means for locking the switch-operating handle in switch-open position whereby to prevent operation of the handle for closing the switch.

Another object of the present invention is the provision of an improved mechanism associated with and operable by the handle and mounted on the casing cover for releasable engagement with the switch-actuating mechanism within the casing.

The above objects of the invention and objects ancillary thereto will be fully understood from the following description considered in connection with the accompanying illustrative drawings.

In the drawings:

Fig. 1 is a perspective view of an enclosed switch embodying the present invention;

Fig. 2 is a perspective view showing the casing cover open;

Fig. 3 is a sectional view on the line 3—3 of Fig. 2;

Fig. 4 is a sectional view on the line 4—4 of Fig. 3;

Fig. 5 is a perspective view of a locking member removed from the switch-operating handle;

Fig. 6 is a view of the inner side of the handle;

Fig. 7 is a view of parts taken along the line 7—7 of Fig. 3;

Fig. 8 is a sectional view on the line 8—8 of Fig. 6, the locking member being removed.

Referring now to the drawings in detail, the switch casing 10 comprises a box 12 and a cover 14 which is hinged to said box at one side thereof as indicated at 16 so that said cover may be swung to closed and open positions as illustrated by Figs. 1 and 2. The switches proper (not shown) which are mounted within the box 12 may be actuated by any suitable mechanism. As here shown the latter may include a shaft 18 connected to the pivoted arms 20 and 22 and operable by a spring-toggle mechanism including a pivoted lever plate 24 which is mounted for pivotal movement about an axis which is parallel to the front of cover 14. As the present invention is not concerned with any specific mechanism for actuating the switch or switches, such mechanism will not be further described, it being noted however that the lever plate 24 is provided with a recess 26 in which the offset end 55

portion 28 of the handle-operated lever 30 releasably engages said lever plate, when the casing cover 14 is closed, to turn said lever plate in either direction about its axis for operating the switch-actuating mechanism to open and close the switch.

The switch-operating handle 32 is mounted for turning movement on cover 14 externally of the latter and is operatively connected to the lever 30, as will hereinafter be more particularly described, said lever being pivotally mounted at one end thereof to a bracket 34 in any suitable way as by a pivot stud or shouldered screw 36. Said bracket is welded or otherwise secured to the inner side of the cover. Handle 32 has a hub or pivotal portion 38 provided on its inner side with a recess 40 (Figs. 6 and 8) which registers with an opening 42 in the cover 14. A bearing plate or disk 44 is positioned in recess 40 and in opening 42. A disk 46 is disposed at the inner surface of cover 14 and is connected to the hub 38 of handle 30 by screws 48 which pass through openings 50 in disk 44 and are threaded into tapped holes 52 in said handle hub. As shown more clearly by Fig. 7, the circular opening 42 in cover 14 has a circumferentially extending part 54 terminating at the edges 56 and 58, and disk 44 has a radial projection 60 which projects into part 54 for movement therein and engages said edge portions 56 and 58 in the "off" and "on" positions of handle 32. Edge portions 56 and 58 and projection 60 of disk 44 thus constitute interengageable means for limiting the movement of the switch handle in opposite directions. Referring to Fig. 6, it will be noted that the recess 40 of the switch handle is provided with a radial extension 62 to receive the tongue 60, and it will be understood that the tongue or extension 60 of disk 44 which fits in recess 62 aids in preventing relative pivotal movement between said disk and handle. The disk 46 is connected to lever 30 by a link 64 which is pivotally connected at its opposite ends to said lever, intermediate the opposite ends of the latter, and to a radially projecting lug or ear 66 on disk 46, by means of the pivot studs 68 and 70 respectively. A spring-pressed ball 72 (Fig. 3) is provided in a bore 74 of handle hub 38 and is engageable in either of a pair of small openings 76 and 78 in cover 14 for preventing free movement of handle 32 when the cover is in its open position and the handle is in either its "on" position or its "off" position.

The handle 32 is provided with a rectilinearly movable locking member 80 slidably movable in a slot 82 of said handle. Said locking member

3

86 has a locking element or projection 84 which slidably fits in a slot 86 provided in disk 44 in registry with the inner end of handle slot 82. The casing cover is provided with a notch 88 into which locking projection 84 is moved when locking member 80 is moved from its retracted or handle-releasing position to its projected or handle-locking position shown in Fig. 1. Locking member 80 has an elongated opening 90 which, as shown in Fig. 3 is disposed internally of the handle hub 38 when the locking member is in its retracted position and which is disposed externally of the handle, as shown in Fig. 1, when the locking member is in its projected position. A removable lock L serves to hold locking member 80 in its handle-locking position. Opening 90 is preferably long enough to receive two or more individual locks, operable by different keys respectively, so that the handle may be locked against operation by a number of authorized persons for purposes well known to those skilled in the art. The locking member is releasably held in its retracted position by a spring 92 which is positioned in an opening 94 provided in said locking member and in a widened part 96 of slot 82. Referring to Fig. 4, it will be noted that one end of the spring bears against the shoulders 98 of slot part 96 while the other end of said spring bears against the edge 100 of the opening 94 of locking member 80. A lateral projection 102 is formed on locking member 80 and is slidable in the recessed part 104 adjacent slot part 96. Slot 82 has a portion 106 which slidably receives the extension 108 of locking member 80. The knurled edge portion 110 of locking member 80 facilitates the projection of said locking member from the handle to its locking position as will be readily apparent. It may be noted that when locking member 80 is inserted in its correct position in handle 38, disks 44 and 46 being subsequently secured to the handle hub, said locking member is held against removal from said handle from the outer side of the cover and can only be removed when the cover is open and disks 44 and 46 are removed. The cover 14 may be locked closed by one or more devices which are well known to those skilled in the art. One such device may comprise the conventional pivoted cover latch 112 carried by the switch box 12 and engageable in an opening 114 of the cover, said latch being provided with an opening 116 for a lock. Another locking device for preventing unauthorized movement of handle 32 from its "off" position may be constituted by any suitable interlock with which the art is familiar for preventing unauthorized opening of the cover.

Provision is also made to enable the handle 32 to be locked in its "on" position when, as is sometimes the case, such locking of the handle is required. For this purpose a notch 115 is provided in cover 14 for engagement by locking projection 84 of locking member 80 when the handle is in its "on" position. It will be noted that in the illustrated form of the invention handle 32 is movable through 90° to and from its "on" and "off" positions so that locking notches 88 and 115 are therefore spaced 90° apart for registry with the slot 82 of the handle in the "off" and "on" positions respectively, thereof, so that said handle can be locked in either of said positions.

It will be noted that as a result of the above described construction of the handle locking means of the present invention it is unnecessary to provide any external projections on the cover or any other auxiliary lock-retaining means on

the cover externally thereof or even internally thereof, except for the locking notch or notches 88 and 115. Further it will be observed that notches 88 and 115 are covered at the outer side of the cover by the inner side of the handle hub 38.

Various changes in the details of construction and in the form and arrangement of the various parts may be made without departing from the underlying idea or principles of this invention within the scope of the appended claims.

Having thus described my invention, what I claim and desire to secure by Letters Patent, is:

1. In a switch casing provided with an operating handle mounted thereon externally of the casing for movement to "off" and "on" positions, said casing having a part provided with an opening through which said handle is operable to actuate a switch disposed within the casing, said handle terminating at the outer side of said casing, means for releasably locking said handle in a predetermined position in relation to said casing, comprising a locking member mounted on said handle for movement from retracted or handle-releasing position to projected or handle-locking position, and means connected to said handle at the inner side of the casing for preventing removal of said locking member from said handle except when the casing is opened, said latter means being a member overlying said opening at the inner side of the casing and operatively engaged with said handle for movement thereby.

2. In a switch casing provided with an operating handle mounted thereon externally of the casing for movement to "off" and "on" positions, said casing having a part provided with an opening through which said handle is operable to actuate a switch disposed within the casing, means for releasably locking said handle in a predetermined position in relation to said casing, comprising a locking member mounted on said handle for movement from retracted or handle-releasing position to projected or handle-locking position, and a notch formed in said casing adjacent said opening to receive the projected locking member, a bearing member on said handle journaled in said casing opening for pivotal movement of said handle, said bearing member having a radial slot and said casing having a notch with which said slot registers in said predetermined position of the handle, said locking member having a locking element which is movable in said slot and into said notch for preventing pivotal movement of said handle.

3. In a switch casing provided with an operating handle mounted thereon externally of the casing for movement to "off" and "on" positions, said casing having a part provided with an opening through which said handle is operable to actuate a switch disposed within the casing, means for releasably locking said handle in a predetermined position in relation to said casing, comprising a locking member mounted on said handle for movement from retracted or handle-releasing position to projected or handle-locking position, and a notch formed in said casing adjacent said opening to receive the projected locking member, a bearing member on said handle journaled in said casing opening for pivotal movement of said handle, said bearing member having a radial slot and said casing having a notch with which said slot registers in said predetermined position of the handle, said locking member having a locking element which is mov-

able in said slot and into said notch for preventing pivotal movement of said handle, said handle having a slot in registry with said slot of the bearing member, and said locking member having a portion projecting outwardly of said handle slot providing a finger piece for use in projecting said locking member to its handle-locking position.

4. In a switch casing having an opening for mounting a handle for turning movement thereon, a handle having a part overlapping the casing externally thereof around said opening, a bearing part journalled in said opening and secured to said handle for mounting the latter for said turning movement, a member secured to said bearing part internally of the casing and overlapping the latter around said opening, said casing having a notch at said opening, said handle and said bearing part having aligned slots which register with said notch when the handle is turned to a predetermined position, and a locking member movable in said slots and into said notch, in said position of the handle, for preventing turning of the handle, said locking member having a locking part normally disposed in said bearing part slot and movable outwardly therefrom into said notch in said position of the handle.

5. In a switch casing having an opening for mounting a handle for turning movement thereon, a handle having a part overlapping the casing externally thereof around said opening, a bearing part journalled in said opening and secured to said handle for mounting the latter for said turning movement, a member secured to said bearing part internally of the casing and overlapping the latter around said opening, said casing having a notch at said opening, said handle and said bearing part having aligned slots which register with said notch when the handle is turned to a predetermined position, and a locking member movable in said slots and into said notch, in said position of the handle, for preventing turning of the handle, and interengaging means on said bearing part and on said casing at said opening for limiting the turning movement of the handle in at least one direction.

6. In a switch casing having an opening for mounting a handle for turning movement thereon, a handle terminating at the outer side of said casing and having a part overlapping the casing externally thereof around said opening, a bearing disk journalled in said opening and secured to said handle for mounting the latter for said turning movement, a disk member secured to said bearing part internally of the casing and overlapping the latter around said opening, a lever having one end pivotally connected to the casing for movement parallel to the plane of said opening and having its other end adapted to engage a switch-actuating mechanism within the casing, and a link pivotally connecting said last mentioned member to said lever intermediate said ends thereof for actuating said lever when the handle is turned.

7. In a switch casing having an opening for mounting a handle for turning movement thereon, a handle terminating at the outer side of said casing and having a part overlapping the casing externally thereof around said opening, a bearing disk journalled in said opening and secured to said handle for mounting the latter for said turning movement, a disk member secured to said bearing disk internally of the casing and overlapping the latter around said opening, a

lever having one end pivotally connected to the casing for movement parallel to the plane of said opening and having its other end adapted to engage a switch-actuating mechanism within the casing, and a link pivotally connecting said last mentioned member to said lever intermediate said ends thereof for actuating said lever when the handle is turned, and releasable means for preventing the actuation of said lever comprising a locking member movably mounted on said handle and engageable with a part of said casing which is externally overlapped by said handle.

8. In a switch casing having a movable cover and a switch operating handle mounted for turning movement on said cover, means for releasably locking said handle in a predetermined position, said handle having a slot and said locking means comprising a locking member slideable in said slot and movable therein from a retracted position to a projected position, and said casing having a part which is engageable by said locking member in the projected position thereof for preventing turning of said handle from said position, said locking member having a lateral projection which overlaps the handle at the inner side thereof for preventing transverse movement of said locking member outwardly of said handle thereby to prevent disengagement of said locking member from the handle.

9. In a switch casing having an opening for mounting a handle for turning movement thereon, said handle terminating at the outer side of said casing, a bearing disk journalled in said opening and secured to said handle for mounting the latter for said turning movement, a disk member secured to said bearing disk internally of the casing and movable therewith, said member overlapping the casing around said opening, and interengaging means on said bearing disk and on said casing at said opening for limiting the turning movement of the handle in at least one direction.

10. In a switch casing having an opening for mounting a handle for turning movement thereon, a bearing part journalled in said opening and secured to said handle for mounting the latter for said turning movement, a member secured to said bearing part internally of the casing and overlapping the latter around said opening, said casing having a notch at said opening, said handle and said bearing part having aligned slots which register with said notch when the handle is turned to a predetermined position, and a locking member movable in said slots and into said notch, in said position of the handle, for preventing turning of the handle, and interengaging means on said bearing part and on said casing at said opening for limiting the turning movement of the handle in at least one direction.

11. In a switch casing provided with an operating handle mounted thereon externally of the casing for movement to "off" and "on" positions, said casing having a part provided with an opening through which said handle is operable to actuate a switch disposed within the casing, means for releasably locking said handle in a predetermined position in relation to said casing, comprising a locking member mounted on said handle for movement from retracted or handle-releasing position to projected or handle-locking position, and a notch formed in said casing adjacent said opening to receive the projected locking member, a bearing member on

said handle journaled in said casing opening for pivotal movement of said handle, said bearing member having a radial slot and said casing having a notch with which said slot registers in said predetermined position of the handle, said locking member having a locking element which is movable in said slot and into said notch for preventing pivotal movement of said handle, said locking member having a part provided with an opening to receive a lock for locking said member in said projected position.

12. In a switch casing having an opening for mounting a handle for turning movement thereon, said handle terminating at the outer side of said casing and having a recess defined therein, said casing and having a bearing disk journaled in said opening and secured in said recess for mounting the handle for turning movement, a disk member secured to said bearing disk internally of the casing and overlapping the latter around said opening, and a locking member mounted on said handle for movement from retracted or handle-releasing position to projected or handle-locking position, said casing having a notch in which said locking member engages in said handle-locking position thereof.

13. In a switch casing provided with an operating handle mounted thereon externally of the casing for movement to "off" and "on" positions, said casing having a part provided with an opening through which said handle is operable to actuate a switch disposed within the casing, means for releasably locking said handle in a predetermined position in relation to said casing, comprising a locking member mounted on said handle for movement from retracted or handle-releasing position to projected or handle-locking position, and a notch formed in said casing adjacent said opening to receive the projected locking member, said handle having a hub portion which overlies said opening and a notch externally of the casing for preventing access into said casing through said opening or notch, said locking member being provided in said hub portion for said movement thereof.

14. In a switch casing having a cover provided with an opening therethrough and a switch operating handle mounted in said opening for turning movement on said cover, means for releasably locking said handle in a predetermined position, said handle having a hub portion provided with a slot and said locking means comprising a locking member movably fitted in said slot and completely closing said slot and movable therein from a retracted position to a projected position, and said casing having a part which is engageable by said locking member in said projected position thereof for preventing turning of said handle from said predetermined position, said handle having a peripheral part which overlies said cover externally of the latter around said opening and said locking member, in all positions of said handle, for preventing access to the interior of said casing through said opening.

15. In a switch casing having a handle movable thereon to and from a predetermined po-

sition, means for releasably locking said handle in said position comprising a locking member bodily movable on said handle to and from a projected or handle-locking position, and a part in fixed relation to said casing releasably engageable by said locking member when said handle is in said predetermined position and said locking member is moved in relation to said handle to said projected position, said handle having a pivotal portion terminating at the outer side of said casing and dimensioned to overlie said casing part for preventing access into said casing through said part, and a member disposed internally of said casing to overlie said casing part internally thereof, said latter member being secured to said pivotal portion whereby said casing part is disposed therebetween.

16. In a switch casing having a handle movable thereon externally thereof to and from two different predetermined positions, means for releasably locking said handle in either of said positions, comprising a part on said casing provided with notches at said positions, respectively, of the handle and a locking member movably mounted on said handle and movable into said notches, respectively, in said predetermined positions of the handle for preventing movement of the handle in relation to the casing, said handle terminating at the outer side of said casing and having a slot in which said locking member is movable to and from its locking position, said slot being in registry with one of said notches in one of said positions of the handle and in registry with the other of said notches in the other position of the handle, and a member disposed internally of said casing to overlie said casing part internally thereof, said latter member being secured to said handle whereby said casing part is disposed therebetween.

17. In a switch casing having an opening for mounting a handle for turning movement thereof, said handle terminating at the outer side of said casing, a bearing element journaled in said opening and secured to said handle for mounting the latter for turning movement, a retaining member secured to said bearing element internally of the casing and overlapping the latter around said opening, and a locking member mounted on said handle for movement from retracted or handle-releasing position to projected or handle-locking position, said casing having a notch in which said locking member engages in said handle-locking position thereof.
